MACHINE FOR KNURLING OR FORMING
TEETH IN AXLES

Charles A. Adams, Ellwood City, and Gomer F. Owens, Wayne Township, Pa., assignors to Mathews Conveyer Company, Ellwood City, Pa., a corporation of Pennsylvania

Application September 17, 1931, Serial No. 563,386
Renewed November 26, 1934

20 Claims. (Cl. 80—5.1)

This invention relates to an improved machine for knurling or forming teeth in the periphery of a cylindrical body such as an axle or shaft.

In the manufacture of various kinds of apparatus as, for example, roller conveyors which usually employ shafts or axles having anti-friction bearings mounted thereon upon which the rollers are supported, it often becomes necessary to provide means for preventing the inner ball races or bearing cones from relatively rotating upon the axles. Heretofore, it has been common practice to fit the bearing cones onto the axles in such a manner that the frictional engagement of the bores of the cones with the axle would prevent the cones from relatively rotating thereon. In some instances, the inner bearing cones have been secured to the axles by means of pins or keys, thereby making it impossible to relatively adjust the bearing cones upon the axles when they become worn. It is desirable that means be provided whereby the cones may be relatively adjusted upon the axles to present new wearing surfaces to the anti-friction elements of the bearing, when the cones become worn.

Roller conveyors usually comprise a plurality of fixed axles upon which the rollers are mounted by means of suitable anti-friction bearings. The axles are usually supported upon and secured to suitable side rails so as to prevent them from relatively rotating when the rollers are operating. The inner cones of the anti-friction bearings must therefore be mounted upon the axles in such a manner that they will not rotate thereon in order to avoid undue wear upon the axle, and it is an object of this invention to provide an improved machine for forming longitudinally extending teeth in portions of the peripheries of the axles adapted to interlock with correspondingly shaped teeth provided in the bores of the inner cones, whereby the latter cannot relatively rotate upon the axles, when in position thereon, but whereby they may readily be relatively adjusted thereon to present new wearing surfaces to the anti-friction elements of the bearings, when necessary.

A further object is to provide a machine comprising a head having a toothed member mounted therein adapted to engage the periphery of an axle and form a plurality of elongated indentations and teeth in the periphery thereof, as said head is rotated.

A further object is to provide a machine comprising a head having a knurling mechanism therein, and a magazine adapted to support a plurality of axles, and means for feeding the axles

from the magazine into the knurling head, one at a time, as the latter is rotated, whereby a portion of the periphery of each axle will be knurled, after which the knurled axle will be discharged from said head onto a suitable receiving means.

A further object is to provide a knurling head comprising a fixed body having means rotatably mounted therein and adapted to receive one end of an axle, and a toothed member being mounted within said head and adapted for relative rotation with respect thereto so that when the axle is conveyed around the axis of said head, said toothed member will engage the periphery thereof and indent the same in a manner to provide a plurality of longitudinally extending teeth and grooves in the periphery thereof.

Other objects of the invention reside in the particular construction of the knurling head including the means for driving the sleeve which receives and feeds the axles one at a time from the receiving to the discharging points of the head; in the means provided within the head for supporting the axle whereby when the latter is engaged by the toothed knurling member, the axle will relatively roll upon a supporting surface as it travels from the receiving to the discharging points of the head; in the means provided for equally distributing around the circumference of the toothed member, the wear resulting from the axle being engaged by said toothed member; in the means provided whereby axles of different diameters and lengths may be knurled upon the same machine by indexing the machine to another size knurling head; in the means provided whereby both ends of an axle may be knurled at the same time; and, in the general construction and arrangement of the parts of the machine whereby the operation of the machine is greatly simplified and its operation made substantially automatic.

Other objects of the invention will appear from the following description and accompanying drawings and will be pointed out in the annexed claims.

In the accompanying drawings, there has been disclosed a structure designed to carry out the various objects of the invention, but it is to be understood that the invention is not confined to the exact features shown as various changes may be made within the scope of the claims which follow.

In the drawings:

Figure 1 is a longitudinal sectional view taken on the line 1—1 of Figure 2, showing a machine with a plurality of knurling heads.

Figure 2 is a cross sectional view on the line 2—2 of Figure 1;

Figure 3 is an enlarged detail sectional view on the line 3—3 of Figure 4 showing the interior construction of one of the knurling heads;

Figure 4 is a cross sectional view on the line 4—4 of Figure 3 showing the means for driving the axle feed plates;

Figure 5 is a cross sectional view on the line 5—5 of Figure 3, showing the knurling member and the means for feeding the axles one at a time from the receiving to the discharge points of the head;

Figure 6 is an enlarged detail sectional view showing one end of an axle positioned in the head and a portion of its periphery being knurled;

Figure 7 is a detail view showing the means for disengaging the drive to index the knurling heads;

Figure 8 is a detail sectional view on the line 8—8 of Figure 5;

Figure 9 is a perspective view showing one end of an axle with a portion of its periphery knurled; and

Figure 10 is a view similar to Figure 1 but showing a machine adapted to simultaneously knurl both ends of each axle as they are fed through the machine.

The novel machine featured in this invention comprises a main supporting shaft 2, preferably tubular in cross-section as shown, and supported in suitable bearing pedestals 3 and 4 secured to suitable base plates 5 mounted upon rails 6—6 as best shown in Figures 1 and 2.

Suitable supporting members 7 and 8 are shown keyed to the supporting shaft 2 adjacent the bearings 3 and 4, and these supporting members support a plurality of knurling heads A, B, and C, which are adapted to knurl axles of different diameters. As the knurling heads A, B, and C, are all of like construction with the exception that they are designed for knurling axles of different diameters, but one such head will be described in detail, like parts being referred to by like numerals.

Each knurling head comprises a body portion 9 preferably cylindrical in cross section and suitably secured to a plate 11 which, in turn, is secured by suitable bolts 12 to the supporting member 7, as best shown in Figure 3. The plate 11 is axially aligned with the bore 13 in the member 7 by suitable means such as indicated at 14 in Figure 3. In like manner, the body portion 9 of the head is axially aligned with the plate 11 by reason of the shoulder 15 provided upon the plate 11. A shaft 16 has one end rotatably supported in the bore 13 of the supporting member 7 and has its opposite end similarly supported in a bearing 17 provided in the supporting member 8.

The means for driving the shaft 16 is best shown in Figure 1, and comprises a coupling member 18 keyed to the reduced end portion 19 of said shaft, and having a cylindrical portion 21 adapted to be received in a counter bore 22 provided in a complementary coupling member 23 which is slidably mounted upon a stub shaft 24 of a suitable speed reducer 25. The reducer 25 is operatively connected to a suitable motor 26 by means of a gear drive 27, shown in Figure 2. The coupling member 23 has a spring-actuated drive pin 28 adapted to be received in a socket 29 provided in the coupling member 18 whereby the shaft 16 may be driven by the shaft 24 of the speed reducer.

Means are provided for disengaging the pin 28 from the clutch member 18 to permit the sup-

porting members 7 and 8 to be rotated about the axis of the main shaft 2, when it is desired to change from one knurling head to another. Such means is best shown in Figure 7 and comprises a hand lever 31 pivoted to a bracket 32, here shown secured to the frame of the speed reducer 25. The lever 31 has a yoke 33 carrying a collar 34 provided with lugs 35 received in an annular groove 36 provided in one end of the coupling member 23. A suitable spring 37 is coiled about the shaft 24 and constantly urges the coupling member 23 in a direction towards the coupling member 18. To disengage the pin 28 from the coupling member 18, the clutch lever 31 is moved from the full to the dotted line position shown in Figure 7, whereupon the clutch member 23 will be moved away from the coupling member 18 to thereby move the pin 28 out of the socket 29. When the clutch member 23 is thus positioned, the shaft 16 is out of driving connection with the speed reducer 25. If desired, the pin 28 may be moved out of driving engagement with the coupling member 18 by manually moving the pin independently of the coupling member 23. This may be accomplished by means of the head 20 of the bolt.

The means within the knurling head which engages the periphery of the axle to form the spaced teeth therein is best shown in Figures 3, 4, and 5, and comprises an external gear 38 suitably secured to the shaft 16 by such means as a key 39. The gear 38 constantly meshes with a plurality of pinions 41 spaced equidistant apart about the circumference of the gear 38 and mounted upon pins 42, each having one end supported in a disk 43 and having their opposite ends supported in a disk 44 as best shown in Figure 3. The pinions 41 are adapted to roll in an internal ring gear 45 fixedly mounted in the body portion 9 of the head by suitable screws 46. By thus interposing the pinions 41 between the gears 38 and 45, when the gear 38 is rotated, the pinions 41 will roll in the ring gear 45 about the axis thereof at a relatively slower rate of speed than the peripheral speed of the gear 38, thereby imparting a rotary movement to the disks 43 and 44.

The opposite end of the body portion 9 of the knurling head is provided with a counterbore 47 in which there are mounted two semi-cylindrical members or shoes 48 secured in position therein by suitable bolts 49. Within the members 48, there is mounted a feeding unit 51 comprising two parts 52 and 53 suitably secured together by such means as bolts 54. The member 52 has a sleeve 55 formed thereon which is secured at its opposite end to the disk 44, so that when the disks 43 and 44 are rotated, a similar motion will be imparted to the feeding unit 51 comprising the parts 52 and 53. The sleeve 55 is preferably provided with a suitable bushing 56 in which the shaft 16 is received, and a similar bushing 57 may be provided exteriorly of the sleeve 55 to provide a suitable bearing for the sleeve in the body portion 9. The feeding unit is shown provided with oppositely disposed notches or recesses 58 adapted to receive the end portions of the axles which are to be knurled, as will subsequently be described.

An annular recess 59 is provided between the parts 52 and 53 of the feeding unit 51, as best shown in Figure 8, which is mounted a toothed knurling member or wheel 61 here shown secured to a hub 62 which, in turn, is secured to the shaft 16 by such means as a pin 63. The toothed periphery of the wheel 61 projects slight-

ly above the bottoms of the recesses 58 provided in the feeding unit 51 so that the teeth on the wheel 61 will indent the periphery of the axles being carried in the notches 58.

5 A tubular member 64 has one end suitably secured to the part 53 of the feeding unit 51 and has its opposite end supported upon the shaft 16 by means of a collar 65 secured to the member 64 as shown in Figure 3. A ring 66 is clamped to the tubular member 64 and has oppositely disposed recesses or notches 67 adapted to be alined with the notches 58 in the carrier 51. The notched ring 66 thus cooperates with the feeding unit 51 to support the axles as they are fed through the knurling head.

10 The means for feeding the axles to the knurling head is best shown in Figures 1 and 2, and comprises a pair of spaced angle irons 68 having their intermediate portions adjustably supported upon a rod 69 which may be fixedly mounted in suitable uprights 71 supported upon the base plates 5. The lower end of the angle iron 68, at the left hand side of the machine when viewed as shown in Figure 1, has a bracket 72 adapted to be attached to a small bracket 73, here shown secured to the periphery of the body portion 9 of the knurling head A. Each knurling head is provided with a similar bracket 73, as shown in Figure 2, to which the bracket 72 of the angle iron 68 15 is attached, depending upon which knurling head is to be used. The angle iron 68 at the right hand side of the machine has a similar bracket 72 adapted to be detachably connected to a spider 20 74. The spider 74 is provided with a feather key 75 adapted to slide in a keyway 76 provided in the shaft 2, whereby the spider may be axially adjusted upon the shaft 2, so as to space the angle irons 68 the proper distance apart to suit 25 the lengths of the axles to be knurled. Suitable means, not shown, are provided for locking the spider 74 to the shaft 2. The angle irons 63—68 thus cooperate to provide a magazine for supporting the unknurled axles, as shown in Figure 2.

30 Radial slots 76 are provided in one end of the body portion 9 of each knurling head, as shown in Figure 5. These slots register with the gaps provided between the ends of the semi-circular members 48, and the bottoms of these slots are substantially alined with the bottom of the counterbore 47 which, it will be noted by reference to Figures 1 and 2, is substantially alined with the upright flange of the angle irons 68. Suitable rails 77 are provided at the opposite side of the knurling head adapted to receive the knurled axles, as best shown in Figure 2.

35 When a plurality of knurling heads are provided in a single machine, as shown in Figures 1 and 2, means are provided for locking each knurling head and its associated parts in alinement with the drive shaft 24 of the speed reducer 25, and also whereby the slots 76 of a selected knurling head may be alined with the discharge ends 40 of the angle iron rails 68 as shown in Figure 2. Such means is shown in Figures 1 and 2, and may consist of a pair of dogs 78 slidably mounted in brackets 79 and each having an operating arm 81 pivotally connected therewith. These arms are secured to a rock shaft 82 mounted in suitable bearings provided upon the brackets 79. The supporting members 7 and 8 secured to the main supporting shaft 2 are preferably triangular in shape as shown in Figure 2, and are provided at 45 their outer extremities with a plurality of notches

58 adapted to receive the terminals of the dogs 78 as clearly shown in Figure 2. Springs 84 constantly urge the dogs 78 in a direction to engage the notches or recesses 83 provided in the supporting members 7 and 8.

10 A suitable foot pedal 85 is secured to the rock shaft 82 whereby the latter may be actuated to move the dogs out of locking engagement with the members 7 and 8. When the dogs are moved out of engagement with their respective notches 15 83 and the pin 28 of the clutch member 23 is moved out of engagement with the clutch member 18 of the knurling head alined with the drive shaft 24, the main supporting shaft 2 may be rotated to move a selected knurling head into 20 alignment with the drive shaft 24, said head being locked in such position by means of the dogs 78 engaging the notches 23 in the supporting members 7 and 8.

25 In the operation of this novel knurling machine, the selected knurling head is alined with the drive shaft 24 of the speed reducer 25 and is locked in such position by means of the dogs 78. The shaft 16 of the selected knurling head is then operatively connected with the drive shaft 24 of the speed reducer 25 by means of the coupling members 18 and 23. The rail 68 at the right hand side of the machine, when viewed as shown in Figure 1 is then relatively adjusted upon the supporting rod 69 so that the spacing between the 30 upright flanges of the two rails 68 may be slightly greater than the overall lengths of the shafts to be knurled.

35 The shafts to be knurled are then placed in the magazine formed by the rails 68, as shown in Figure 2, whereby some of the axles will enter the slot positioned at the upper right hand portion of the knurling head, when viewed as shown in Figure 2, so that the lower axle will be positioned in the notches provided in the carrier 51, one 40 end of the axle being supported in the notch 58 of the feeding unit 51 and the opposite end of the axle being supported in one of the notches 67 of the ring 66, as indicated in dotted lines in Figure 3. As the shaft 16 of the knurling head is rotated, the external gear 38 secured to this shaft will cause the pinions 41 to roll around in the internal ring gear 45, whereby the driving disks 43 and 44 will be rotated at a relatively slower speed than the gear 38, whereby a similar motion will be 45 imparted to the sleeve 55 and therefore the feeding unit 51 including the ring member 66, which rotates as a unit with the feeding unit 51 because of the tubular member 64 being secured to the part 53 of the feeding unit. The collar 65 at the 50 end of the member 64 rotates upon the shaft 16. Such rotation of the feeding unit will permit the axle positioned in the notches 58 and 67 of the feeding unit to be conveyed from the magazine around the axis of the shaft 16 until it reaches 55 the slot 76 diametrically opposite, whereupon the knurled axle will be discharged from the head onto the receiving rails 77.

60 The knurling of the axle is effected by the teeth of the knurling wheel 61 engaging and indenting that portion of the peripheral surface thereof alined with the knurling wheel 61, and because of the peripheral speed of the knurling wheel being relatively greater than the speed of the feeding unit 51, thereby causing the axle being knurled to constantly rotate in the notch 58 in the knurling head as it is being carried from the receiving slot 76 adjacent to the magazine, around to the discharge slot provided at the receiving rails 77. During movement of the shaft 75

from the receiving to the discharge slots, it will roll upon the inner surface 86 of one of the semi-circular members 48, the latter being relieved at their intermediate portions, as shown at 87 in Figure 3 to provide clearance for the teeth 88 being formed in the periphery of the axle. (See Figure 9.) By thus forming the teeth in the periphery of the axle, the latter will not be weakened as no material is cut away, the material of the periphery of the axle merely being upset by pressure to form the teeth as shown.

Because of the knurling wheel being driven, as herein before described, the teeth formed in the periphery of the axle will be accurately spaced, so that bearing cones having their bores provided with correspondingly shaped teeth may be readily fitted onto the axle and interlocked therewith to prevent relative rotation of the bearing cones thereon. Also, by providing correspondingly shaped teeth on the periphery of the axle and in the bore of the bearing cone, the latter may readily be rotatively adjusted upon the axle by simply moving it out of engagement with the teeth 88 thereof and relatively rotating it upon the axle, and then again moving it into interlocking engagement with the teeth 88 of the axle.

The machine is automatic in operation, it being only necessary to keep the magazine rails 68 supplied with unknurled axles. Because of the feeding unit being provided with two notches 50, as shown in Figure 5, as soon as one axle has been knurled and is discharged from one of the notches on the feeding unit onto the receiving rails 77, the notch at the opposite side of the feeding unit will be aligned with the magazine whereby another unknurled axle will be delivered to the feeding unit. Thus, only one axle is being knurled at a time. During the period that an axle is being knurled, the following unknurled axle will be supported upon the peripheries of the parts 52 and 53 of the feeding unit 51, as will readily be understood by reference to Figure 1, and as indicated by the dotted lines in Figure 5. Also, because of the differences in diameters of the gears 38 and 45, the periphery of the knurling wheel 61 will constantly change its position with respect to the notches 50 so that all of the teeth in the knurling wheel will be used an equal amount in the operation of knurling a plurality of axles, thereby evenly distributing the wear over all of its teeth. By providing the machine with three knurling heads, axles of different diameters may be knurled upon the same machine, thereby economizing in space and, at the same time, making a very compact and efficient machine.

Figure 10 illustrates a knurling machine similar to the one illustrated in Figures 1 and 2, but having two knurling heads mounted upon each shaft 16, whereby both ends of each axle may be knurled at the same time. In the construction here shown, the knurling heads on each shaft 16 are made right and left hand and are arranged as shown. The head at the right hand side of the machine is mounted for longitudinal adjustment upon the shaft 16 and is supported upon a member 89 adjustably secured to the main supporting shaft 2 by means of a threaded rod 91 mounted in the supporting members 7 and 8, and having a threaded connection with the member 89. One end of the rod 91 is held against longitudinal movement in the supporting member 7, while the opposite end portion 92 thereof is preferably squared to receive a suitable wrench or other instrument whereby the rod may be rotated to longitudinally translate the mem-

ber 89 upon the supporting shaft 2. Thus, by relatively rotating the rod 91, the knurling heads carried by the member 89 may be moved towards or away from the fixed heads provided at the opposite end of the machine.

The member 89 is provided with a feather key 93 slidable in the keyway 76 provided in the shaft 2. This feather key prevents the member 89 from relatively rotating upon the main shaft 2 and thus assures that each pair of knurling heads will always be axially aligned with each other. In the construction shown in Figure 10, the magazine rail 68 at the right hand side of the machine is supported in a manner similar to the rail 68 at the opposite end of the machine, each knurling head at the right hand side of the machine being provided with a bracket 73 similar to the corresponding brackets provided on the knurling heads provided at the left hand side of the machine.

In the drawings and specification, we have shown and described the machine as being an independent machine adapted for use only to knurl axles or similar devices. It is to be understood, however, that in some instances, it may be desirable to use only a single knurling head which may be provided with means for supporting it upon the bed of an ordinary lathe and then connecting the shaft 16 to the head of the lathe. When thus operated, the axles may be manually fed into the knurling head and the resultant work formed upon the axles will be identically the same as that performed in the machine shown in Figure 1.

The term "positive drive" as used in the specification and claims is used to denote a drive wherein slippage between the driving and driven element cannot occur. For example, a sprocket and chain or gearing is considered to be a positive drive, whereas a friction drive is not considered to be a positive drive within this definition.

We claim as our invention:

1. In a machine of the class described, a fixed head having a feeding unit mounted therein and adapted to receive one end of an element to be knurled, a toothed member mounted within said head and adapted for relative rotation therein, and toothed means for operating said feeding unit at a relatively slower speed than said member whereby said toothed member will engage and indent a portion of the periphery of said element and form a plurality of teeth therein spaced equidistant apart.

2. In a machine of the class described, a head having a feeding unit mounted therein and adapted to receive one end of an element to be knurled, an annular toothed member mounted within said head and adapted for relative rotation therein, and a positive drive for operating said feeding unit at a relatively slower speed than said toothed member and in the same direction, thereby causing the toothed member to engage and relatively rotate the element in said support and thereby form a plurality of teeth in its periphery, spaced equi-distant apart.

3. In a machine of the class described, a fixed head having a shaft mounted therein, a feeding unit also mounted in said head and having an annular recess facing inwardly, a toothed member mounted in said recess and secured to the shaft, said feeding unit having a notch in its periphery for supporting an axle in position to engage the periphery of said toothed member whereby said member will indent and upset a portion of the periphery of the axle to provide

- a plurality of longitudinally extending teeth therein spaced equidistant apart, and a gear mechanism for rotating said feeding unit in the same direction as the toothed member, but at 5 a relatively slower speed, whereby said member will relatively rotate the axle in said notch.
4. In a machine of the class described, a head provided with a suitable support, a shaft rotatably mounted in said head, a feeding unit movably mounted within said head and having a notch in its periphery for receiving an axle to be knurled, gear means on said shaft for driving said feeding unit in the same direction as the shaft but at a relatively slower speed, a knurling 10 wheel secured to the shaft and having its toothed periphery arranged to engage a portion of the periphery of an axle supported in the notch in said feeding unit, and means within said head for holding the axle in said notch during rotation of the feeding unit whereby when said parts are operated, said knurling wheel will engage and upset a portion of the periphery of said axle around the circumference thereof and form a plurality of longitudinally extending teeth therein, spaced equidistant apart.
5. In a machine of the class described, a head having a shaft rotatably mounted therein and provided at one end with a counterbore, a feeding unit movably mounted within said counterbore and having notches in the periphery thereof for receiving axles to be knurled, means on said shaft for driving said feeding unit in a corresponding direction of rotation but at a relatively slower speed, a knurling wheel secured to the shaft and having its toothed periphery projecting above the bottoms of the notches in said feeding unit and adapted to engage the periphery of an axle supported in one of said slots, and members fitted in said counterbore and arranged to retain the axles in said notches whereby when said parts are operated, said knurling wheel will engage the portions of the peripheries of said axles supported in said notches, whereby a plurality of longitudinally extending teeth are formed therein, spaced equidistant apart.
6. A knurling machine comprising a head provided with a suitable support, a shaft rotatably mounted in said head, an external gear keyed to the shaft, an internal gear secured in said head, a plurality of pinions operatively connecting together said gears, a feeding unit operatively connected with said pinions and having means adapted to support one end of an axle to be knurled, a knurling wheel secured to said shaft and having its periphery positioned to engage an axle supported in said feeding unit, and means for driving said shaft whereby said knurling wheel will engage and indent a portion of the periphery of the axle and, at the same time, cause said axle to be relatively rotated in said feeding unit whereby a plurality of equally spaced teeth will be formed in the periphery of the axle around its circumference.
7. A knurling machine comprising a head having a shaft rotatably mounted therein, a feeding unit having notches in its periphery each adapted to support one end of an axle to be knurled, said feeding unit having an annular recess therein, a knurling wheel mounted within said recess and secured to said shaft and having its periphery projecting above the bottoms of said notches and adapted to engage axles supported therein, a gear mechanism within said head operatively connecting said feeding unit with said shaft and adapted to rotate the feeding unit in the same direction but at a relatively slower speed whereby said knurling wheel will cause the axles in said notches to be rotated therein and thereby indent a portion of the periphery of the axle whereby a plurality of equally spaced teeth will be formed in the periphery of the axle around its circumference.
8. A knurling machine comprising a head provided with a suitable support, a shaft rotatably mounted in said head, an external gear keyed to the shaft, an internal gear secured in said head, a plurality of pinions operatively connecting together said gears, a feeding unit operatively connected with said pinions and adapted to support one end of an axle to be knurled, said feeding unit having an annular recess therein, a knurling wheel mounted within said recess and secured to said shaft and having its periphery positioned to engage an axle supported in said feeding unit, and means for driving said shaft whereby said pinions will be operated to rotate said feeding unit at a relatively slower speed than the speed of said shaft, and whereby said knurling wheel will be rotated synchronously with said shaft and thereby engage and indent a portion of the periphery of the axle and, at the same time, cause said axle to be relatively rotated in said feeding unit whereby a plurality of equally spaced teeth will be formed in the periphery of the axle around its circumference.
9. In a machine of the class described, a plurality of knurling heads, a support for said heads mounted for rotary adjustment, whereby a selected head may be positioned to receive axles to be knurled, means within each head for knurling a portion of the periphery of an axle, means for feeding the axles to the selected head, and means for operating the knurling mechanism in the said head, whereby an axle fed thereto will be knurled and discharged from the head onto a suitable receiving means.
10. A knurling machine comprising a main shaft, a plurality of knurling heads suitably supported upon said shaft and each adapted to knurl a different sized axle, means for locking said shaft in an adjusted position whereby a selected knurling head may be positioned to receive axles to be knurled, and an operating mechanism for actuating the knurling mechanisms of said heads, said operating mechanism being common to all of said heads.
11. A knurling machine comprising a main shaft, a plurality of knurling heads suitably supported upon said shaft and each adapted to knurl a different sized axle, means for locking said shaft in an adjusted position whereby a selected knurling head may be positioned to receive axles to be knurled, an operating mechanism for actuating the knurling mechanisms of said heads, and means for feeding the axles to the knurling mechanism of the selected head, one at a time.
12. A knurling machine comprising a main shaft having a supporting member mounted at each end thereof, a plurality of shafts mounted in said supporting members and spaced equidistant apart and each supporting a knurling head, said heads being adapted to knurl shafts of different diameters, a knurling mechanism in each head, a lock for securing said supporting members in adjusted position whereby a selected knurling head may be positioned to receive axles to be knurled, a common driving mechanism for said knurling heads, and means for operatively connecting the selected knurling head with said driving mechanism.

13. A knurling machine comprising a main shaft having a supporting member mounted at each end thereof, a plurality of shafts mounted in said supporting members and spaced equidistant apart and each supporting a knurling head, said heads being adapted to knurl shafts of different diameters, a knurling mechanism in each head, a lock for securing said supporting members in adjusted position whereby a selected knurling head may be positioned to receive axles to be knurled, means for feeding the unknurled axles to the selected head, and a driving mechanism for said knurling heads.
14. A knurling machine comprising a main shaft having a supporting member mounted at each end thereof, a plurality of shafts mounted in said supporting members and spaced equidistant apart and each supporting a knurling head, said heads being adapted to knurl shafts of different diameters, a knurling mechanism in each head, a lock for securing said supporting members in adjusted position whereby a selected knurling head may be positioned to receive axles to be knurled, means for feeding the unknurled axles to the selected head, one at a time, and a common driving mechanism for said heads comprising means for operatively connecting it with the selected knurling head.
15. In a machine of the class described, a drive shaft, a toothed member secured to said shaft, a feeding unit adapted to receive an element to be indented and feed it into engagement with the toothed periphery of said member, whereby its surface will be indented, and a positive driving connection between said shaft and said feeding unit by which the latter will be positively driven at a predetermined slower speed than said toothed member to thereby cause the indentures impressed in the surface of said element to be spaced equidistant apart around the entire circumference thereof.
16. In a machine of the class described, a drive shaft, a toothed member secured thereto for direct rotation therewith, a feeding unit adapted to receive an element to be indented and feed it into engagement with the toothed periphery of said member, whereby its surface will be indented, and a gear drive operatively connecting said feeding unit to said shaft adapted to drive the feeding unit in the same direction as said member, but at a relatively slower speed, whereby the element will be relatively rotated in said feeding unit to cause a portion of its periphery to be indented around the entire circumference thereof.
17. In a machine of the class described, a head having a feeding unit mounted therein and provided with a notch adapted to receive one end of an element to be knurled, a member concentrically mounted within said head and having a toothed periphery projecting above the bottom of said notch, means within said head for retaining the element in said notch whereby said toothed member may engage and indent a portion of the periphery of said element and form a plurality of longitudinally extending teeth or serrations in its periphery, and a gear drive for operating said feeding unit at a relatively slower speed than said toothed members and maintaining a predetermined speed ratio between the feeding unit and said toothed member.
18. In a machine of the class described, a head having a feeding unit mounted for rotation therein, a toothed member mounted within said feeding unit and adapted for relative rotation with respect thereto, said feeding unit having means for supporting an axle in position to engage the periphery of said toothed member whereby said member will indent and upset a portion of the periphery of the axle to form a plurality of longitudinally extending teeth spaced equidistant apart, and positive means for maintaining a predetermined speed ratio between the feeding unit and said toothed member.
19. In a machine of the class described, a head having a shaft mounted therein, a feeding unit also mounted in said head and operatively connected with said shaft, a toothed member within the feeding unit and secured to the shaft for direct rotation therewith, and said feeding unit having notches therein for supporting an axle in position to engage the periphery of said toothed member whereby said member will indent and upset a portion of the periphery of the axle to provide a plurality of longitudinally extending teeth spaced equidistant apart around the circumference of the axle, and positive means for maintaining a predetermined speed ratio between the feeding unit and said toothed member.
20. In a machine of the class described, a head provided with a suitable support, a shaft rotatably mounted in said head, a feeding unit movably mounted within the head and having means for receiving an axle to be knurled, a knurling wheel secured to the shaft and having its toothed periphery arranged to engage a portion of the periphery of an axle supported in said feeding unit whereby when said parts are operated, said knurling wheel will engage and upset a portion of the periphery of said axle around its circumference and form a plurality of longitudinally extending teeth therein spaced equidistantly apart, and a gear mechanism for driving the feeding unit at a relatively slower speed than said knurling wheel.
